UNITED STATES PATENT OFFICE

159,783

PRINTING ATTACHMENT FOR ROLL OF PAPER

Lee Carver, Birmingham, Ala.

Application June 6, 1949, Serial No. 3,070

Term of patent 14 years

(Cl. D64—11)

To all whom it may concern:

Be it known that I, Lee Carver, residing at Birmingham, in the county of Jefferson and State of Alabama, have invented a new, original, and ornamental Design for Printing Attachment for Roll of Paper, of which the following is a specification, reference being had to the accompanying drawing, forming part thereof, in which Fig. 1 is a perspective view of the printing attachment for roll of paper, showing my new design; and Fig. 2 is a front elevational view thereof. The other end of the unit, not shown, is substantially like the end shown.

I claim:

The ornamental design for a printing attachment for roll of paper, as shown and described.

LEE CARVER.
